ABSTRACT: A presettable electrical switch instrument having condition responsive sensitivity for opening and closing an electrical circuit. A magnet, movable in response to condition changes, actuates a reed switch which triggers a switching module for appropriate actuation of the circuit to be controlled. The specific component assembly enables instrument operation at extremely close preset differentials while affording enhanced selective interchangeability between normally open and normally closed operation.

ELECTRICAL SWITCH INSTRUMENT

CROSS REFERENCES TO RELATED APPLICATIONS

Application Ser. No. 671,438 filed Sept. 28, 1967, now U.S. Pat. No. 3,482,196 entitled "Mercury Switch Controller."

BACKGROUND OF THE INVENTION

1. The field of art to which the invention pertains includes the art of electricity, circuit markers and breakers as specifically including the art therein pertaining to switch instruments operative by fluid pressure or other force and motion-producing devices.

2. Condition responsive switch instruments for various control purposes are well known in the industry and are available from any sources of manufacture. Common among the switch instruments commercially marketed are those in which the switching element comprises either a mercury tilt bulb or a magnetically actuated member with mercury wetted contacts which appropriately make or break a circuit in response to condition changes to which the condition responsive element is sensitive. Frequent requirements of these switches are that the contacts be hermetically sealed and/or that they be operative between differential limits to both make and break the circuit at conditions determined and field set in accordance with customer requirements. While these prior devices work well under conditions commonly encountered, they are inherently characterized by the inability to be satisfactorily serviceable under certain conditions required for specialized applications.

By way of example, the magnetically actuated type instrument has a limited current carrying capacity imposed by the small contacts and light moving parts. High current ratings are not possible to obtain at the same time it is desired to minimize differential between switching points owing to the force and motion differential involved. As a practical measure, such instruments are limited to a current rating of about one-half amp in order to obtain switching differentials of 2 percent or less. The mercury-type switch, on the other hand, can carry heavier currents but requires a gravity shifting of the mercury glob to and from contacts in response to tilt movement by either a pressure or temperature sensitive element. Accordingly, a minimum range of operation is required for shift of the mercury and differential operation less than a minimum of about 5 percent is impossible to obtain.

Moreover, because these switch instruments are in such wide commercial use, they are mass produced to be readily available for meeting the requirements of the markets they are to serve. However, control situations for which these instruments are employed alternatively require that they be operative as either normally open, i.e. in open circuit relation in the absence of a preapplied closing force, or be normally closed, i.e., in closed circuit relation in the absence of a preapplied opening force. Accordingly, it has been necessary for manufacturers to make and for suppliers to stock separate switch instruments providing both types of switching action to satisfy customer needs on demand. Various techniques have been employed to render the operation interchangeable including the obvious technique of instrument disassembly to turn the mercury bulb end for end. An improved technique for obtaining interchangeable operation is disclosed in the aforementioned cross referenced application Ser. No. 671,438 requiring a minimum degree of manual component interchange in the linkage system.

At the same time, certain industries cannot tolerate the presence of mercury while other industrial applications frequently require the switch to have a high current capacity, neither objective of which could be conveniently satisfied by the prior type switch instruments.

SUMMARY

This invention relates to control instruments and particularly to electrical control switch instruments operative in response to a condition sensitive element such as a Bourdon tube, bimetallic thermostatic element, or the like. More

specifically, the invention relates to a control switch instrument employing solid state components and operative in response to a force transmitting unit within differential limits decreased below that which has been possible with switch instruments previously known. In addition the switch hereof simultaneously affords a higher current carrying capacity than was possible with similar prior art instruments while eliminating the objections to mercury and enabling a field set adjustment for normally closed or normally open operation without requiring a mechanical interchange of the linkage mechanism.

In accordance herewith, the instrument is comprised of a reed switch carrying a relatively small current and actuated by a relatively light, permanent magnet movable by a Bourdon tube in response to pressure changes in the system being controlled. The reed switch in turn triggers or pilots a solid state switching module having a relatively high current capacity and connected to the circuit in which the system condition is to be maintained. Because of the light weight and low forces involved in the actuating mechanism, extremely close differential performance, substantially less than previously possible with prior art devices, is easily and accurately achieved. By simply rotating the reed switch manually on its mount through a small angular displacement whereby the magnet either approaches or departs from the reed switch in response to a given directional movement of the Bourdon tube, the entire instrument can be readily and simply adapted in the field for either normally open or normally closed circuit response.

It is therefore an object of the invention to provide a novel control switch instrument sensitive to condition changes.

It is the further object of the invention to provide a novel differentially operable control switch instrument capable of operating accurately within decreased differential limits in response to condition changes than has been possible heretofore.

It is the further object of the invention to provide a novel control switch instrument as in the aforesaid objects simultaneously having a higher current carrying capacity than has been previously characteristic.

It is the still further object of the invention to provide a novel control switch instrument capable of being field set for either normally open or normally close operation with increased ease and without either mechanical substitutions or changes as has been customary in the prior art.

BRIEF DESCRIPTION OF THE DRAWINGS

FIG. 1 is a front view partially broken away illustrating an exemplary control instrument employing a switch operable in accordance with the invention hereof;

FIG. 2 is an end elevation of FIG. 1 taken sectionally through the cover;

FIG. 3 illustrates the relationship of the component elements for normally open operation of the switch;

FIG. 4 is a fragmentary view similar to FIG. 3 and illustrating the relationship of the component elements for normally closed operation of the instrument;

FIG. 5 is an end elevation of the pivotal magnet supporting bracket;

FIG. 6 is an enlarged side elevation of the reed switch subassembly;

FIG. 7 is a sectional elevation taken substantially along the lines 7-7 of FIG. 6;

FIG. 8 is a sectional view of the solid state switch module subassembly; and

FIG. 9 is an electrical circuit diagram partially schematic illustrating the circuit relation between the solid state switch assembly and the reed switch components.

Referring now to FIGS. 1 and 2, there is illustrated a condition responsive switch instrument which generally may be of a type disclosed in U.S. Pat. No. 3,225,622 and incorporated herein by reference although not to be considered a limitation of the invention hereof. The instrument 10 is comprised of a casing 11 including a generally cup-shaped housing 12. En-

closed in the front open end of the housing is a transparent glass or crystal 13 secured by means of a bezel or ring 14. Disposed within the housing is a back plate 18 secured to the rear housing wall. Contained on the back plate mounted dependent therefrom is a fitting or socket 19 extending externally of the housing and adapted to be connected to a source of fluid pressure to which the instrument is to respond.

Within the casing is supported a Bourdon tube 20 connected in fluid communication at its fixed end to socket 19 for receiving fluid pressure supplied thereto. The free end of the tube 20 is connected to one end of a pivot link 21 which has its other end connected via a pin 22 and slip washer 23 to a beam 26. As can be seen, the beam 26 comprises a generally elongated sheet metal member having an elongated slot 27 extending longitudinally thereof. Mounted on this portion of the beam is a clamp 28 having a generally U-shaped cross section to embrace the beam and is held thereon by clamp screw 30 extending through the slot 27 and which can be adjustably located therein. The screw 30 includes an extension in the form of a pin 32 supported at its opposite end in a secured bracket 33 to provide a fulcrum pivot for the beam in response to forced movement transmitted from the Bourdon tube. Also provided in the instrument are arms 35 and 36 by which the differential operating set points of pointers 37 and 38 respectively can be translated to the instrument operation as more clearly and fully described in the aforementioned U.S. Pat. No. 3,225,622.

Switching action is effected from pivotal movement of beam 26 being connected to a switch bracket assembly 40. As will be explained, a magnet 64 carried by the bracket operates a reed switch 42 responsive to the magnetic field when within proximity and which in turn triggers a solid state switching module 44. The latter preferably comprises a Triac which performs the switching operation via leads 45 and 46 connected to the system being controlled.

Bracket assembly 40 is more fully shown in FIGS. 3-5 which will now be described. The assembly includes a bracket arm 50 secured at its lower end to a U-shaped base 51 having depending legs through which to laterally receive a fixed shaft 52 defining a pivot axis thereof. A slip washer 53 laterally secures the base to the shaft. Connecting the base to the beam 26 is a hand compressible spring clip 55 supported on laterally extending pivot pin 56 and having longitudinal openings therein in which to secure the leftmost end of the beam as viewed in FIG. 3. The upper portion of the bracket arm is hooked over to provide a gap 57 between spaced legs 58 and 59. Interposed between the legs to limit bracket pivot in either direction is a fixed shaft 60 extending secured from the back wall 18. At the topmost portion of the bracket arm is a laterally offset foot 63 on which elongated magnet 64 is secured at its underside. A counterclockwise movement of linkage 21 caused by the Bourdon tube likewise produces a counterclockwise movement of the bracket arm 50. Maximum arm movement is defined by the gap distance 57 until leg 59 is displaced into engagement against shaft 60 at which time foot 63 and magnet 64 are at the location shown dashed. In a preferred embodiment the magnet 64 is of about one-fiftieth ounces being about one-half inch in length with a cross section of approximately $1/16 \times 1/16$ inches. By virtue of its supported spacing from the pivot axis, minimum mass of the magnet avoids undesirable moment forces when operative as in FIG. 3.

The reed switch assembly 42 as shown in FIGS. 6 and 7 includes a plastic housing 70 having a clevis connection 71 at its lower section for mounting on the shaft 60. Screw 72 extending through washer 77 and speed nut 78 secures the housing onto the shaft in a desired position as will be explained. At the upper end of the housing, there is a recess supporting a tubular envelope 73 containing the reed switch 74 having outwardly extending leads 75 and 76. These latter leads in turn are each solder connected to wire leads 79 and 80 connected to a terminal board 81 (FIG. 9) and which are effective for triggering switching module 44. Sealing envelope 73 within the housing

is a potting compound 84 such as an epoxy or silicone which has the desirable properties of electrical insulation, moisture proof and otherwise provides physical protection to the reed switch and lead wires.

5 Switching module 44 can best be understood by reference to FIGS. 8 and 9 and is of a solid state unit type providing a switching Triac with gate resistor and spike filter. In a preferred embodiment, this unit is commercially available as G. E. model SC 45 B characterized by voltage and current ratings appropriate for these purposes in a general industrial control switch instrument. The unit includes an enclosing aluminum case 87 housing components including a Triac 88 mounted to the case through insulating bushing 86 via nut 89 and insulating washers 90 and 91.

10 15 Lead 94 connects the nut end 89 of the Triac to terminal board 81 whereat it connects to reed switch trigger lead 79. Reed switch lead 80 likewise connects to the terminal board whereat it ties in with lead 93 which completes the trigger or 20 gate circuit through gate resistor 92 to gate terminal 101 on the Triac. The spike suppression filter, for protection against line transients, comprises capacitor 95 and resistor 96 which are connected in series through lead 97 between the Triac main control terminals 102 and 103. External leads 45 and 46 25 are connected at terminal board 81 to leads 98 and 94 respectively.

To electrically insulate and physically protect the entire assembly 44, it is potted with an insulating compound such as an epoxy or silicone and otherwise conforms to the requirements 30 of the Underwriters Laboratory. Triac heat is transferred to the air by way of the heat sink comprised of the aluminum case 87 and potting compound as well as to the back of housing 12. A coating of heat-conductive compound is employed to reduce the thermal resistance at the joint between the assembly 44 and switch housing 12.

35 In operation, movement of the Bourdon tube in response to pressure changes in the system being controlled, effects movement of beam 26 and consequent pivoting of bracket assembly 42 about pivot axis 52. The reed switch assembly 42 is 40 mounted on post 60 set with the reed switch 74 prepositioned proximally corresponding at either extreme travel limit to be effected by bracket 50 in its pivotal displacement. As shown in FIG. 3, the reed switch is displaced from magnet 64 at a position representing a normal operation of the controller such as 45 normally open, until the magnet is pivoted counterclockwise to energize the reed switch by the imposed magnetic field thereof. That is, for normally open operation this latter condition represents movement of the magnet toward the reed switch, for example, in response to increased system pressure 50 requiring the circuit to be closed.

To change controller operation from the normally open condition of FIG. 3 to the normally closed condition of FIG. 4, the reed switch need only be rotated on post 60 through a small angle until within the magnetic field of magnet 64 in the normal condition of the instrument, i.e. the reed switch is 55 constantly actuated in the absence of increased pressure movement exerted by the Bourdon tube. Subsequent movement of the Bourdon tube in response to a pressure rise effects pivotal displacement of bracket 50 removing the magnet from the reed switch to the position shown dashed in FIG. 4 permitting the reed switch to open. Therefore, by the simple angular presetting of the reed switch on post 60, operation of the switch can be easily and optionally interchanged between normally open and normally closed operation of the control instrument.

60 65 By the above description there is disclosed a novel condition responsive control switch instrument for operating system equipment at desirable differential limits. Since making and breaking contact can be effected with the mere slight shift of the magnetic field by appropriate displacement of the magnet, operation at minimum differential limits are possible which are substantially less than permitted by prior type switch controllers. At the same time, since the operating contacts need 70 not carry the system current but operate as an intermediate

pilot or trigger switch, the instrument is capable of simultaneously operating with a higher current carrying capacity than has been previously known. Moreover, the appropriate required operating condition for either normally closed or normally open operation can be manually done in the field with the mere use of a screw driver without requiring any substitution or replacements of mechanical components. This latter feature not only lends versatility to the instrument but highly simplifies the problem which has previously been regarded as difficult in production equipment. Notwithstanding the advantageous features afforded by the controller switch hereof, its manufacturing cost is comparably less by virtue of the simplified assembly by which these improved results are attained.

Since many changes could be made in the above construction and many apparently widely different embodiments of this invention could be made without departing from the scope thereof, it is intended that all matter contained in the drawings and specification shall be interpreted as illustrative and not in a limiting sense.

1 claim:

1. In a condition responsive electrical controller instrument operative within differential condition limits for controlling a condition to be maintained and including a housing, differential limit means comprising a first operable limit representing a first condition magnitude at which a control operation can occur, a second operable limit different than said first operable limit and representing a second condition magnitude at which a control operation can occur and between which limits an operative condition existing at one operable limit is maintained until the other operable limit is reached, settable means to adjustably preset the differential operating limits at which the instrument is to be operatively responsive for opening and closing a circuit to which it is connected, and a force transmitting unit within said housing responsive to condition changes for emitting movement correlated thereto, the improvement comprising within said housing:

- a. a magnetically actuatable reed switch for opening and closing a circuit to which it is connected;
- b. a magnetic member movable by said force transmitting unit toward said reed switch in response to a first form of condition change and away from said reed switch in response to a second form of condition change to effect opening and closing of the connected reed switch circuit at the differential limits preset by said settable means; and
- c. a second switch for connection to the circuit to be controlled and operably triggered by actuation of said reed switch.

2. In the condition responsive controller instrument of claim 1 in which said second switch is comprised of solid state elements.

3. In the condition responsive controller instrument of claim 2 in which said second switch is mechanically protected in an electrically insulating potting compound.

4. In the condition responsive controller instrument of claim 2 in which the force transmitting unit is a Bourdon tube connected via a mechanical linkage to via support for said mag-

netic member.

5. In the condition responsive controller instrument of claim 2 including presetable means permitting interchangeability between relative operating locations of said reed switch and magnetic member to optionally preselect between normally open and normally closed operation of the instrument at the differential conditions preset by said settable means.

6. In the condition responsive controller instrument of claim 5 in which said presetable means includes a support for said reed switch, and means permitting displacement of said reed switch on said support between a first position relative to the magnetic member in which the instrument is operative as normally closed and a second position relative to the magnetic member in which the instrument is operative as normally open.

7. In the condition responsive controller instrument of claim 6 in which said reed switch support comprises a post and said displacement is angular thereon.

8. A condition responsive controller instrument comprising:

- a. a housing;
- b. a force transmitting unit operative in response to sensed condition changes for emitting movement correlated thereto;
- c. selection means operable to preselect magnitude of sensed condition at which desired response is to be effected;
- d. a reed switch magnetically actuatable between open and closed relation from a normal relation at condition magnitudes below a magnitude selected by said selection means to the other relation at condition magnitudes above a magnitude selected by said selection means;
- e. a magnetic member movable by said force transmitting unit toward and away from said reed switch to effect actuation thereof at a condition magnitude operably selected by said selection means; and
- f. means to displace the magnetic member and reed switch locations relative to each other to preset the instrument between normally open and normally closed operation for a condition magnitude operably selected by said selection means.

9. A condition responsive controller instrument according to claim 8 in which said means to displace relative locations of said magnetic member and reed switch includes a stationary support for said reed switch and means permitting displacement of said reed switch on said support between a first position relative to the magnetic member in which the instrument is operative as normally closed and a second position relative to the magnetic member in which the instrument is operative as normally open.

10. A condition responsive controller instrument according to claim 9 in which said reed switch support comprises a post and said displacement is angular thereon.

11. A condition responsive controller instrument according to claim 9 in which said force transmitting unit is a Bourdon tube movable in response to condition changes and said magnetic member is operatively connected to the movable end of said Bourdon tube for movement therewith.
